United States Patent Office

Des. 187,345
Patented Mar. 1, 1960

187,345

BOTTLE OR SIMILAR ARTICLE

Brooks D. Fuerst, Sylvania, Ohio, assignor to The Squirt Company, Sherman Oaks, Calif., a corporation of California

Application February 24, 1958, Serial No. 49,761

Term of patent 14 years

(Cl. D58—8)

Fig. 1

The side not shown is the same as the side shown.

I claim:

The ornamental design for a bottle or similar article, as shown and described.
